Patented Aug. 30, 1960

188,719

PORTABLE CAFETERIA COUNTER UNIT

Delmar D. Rhoads, 3230 S. Calhoun St., Fort Wayne, Ind.

Filed June 9, 1958, Ser. No. 51,256

Term of patent 14 years

(Cl. D14—3)

Des. 188,719

PAGE 2

Figure 1 is a perspective view of a portable cafeteria counter unit showing my new design;

Figure 2 is a top view of the portable cafeteria counter unit illustrated in Figure 1;

Figure 3 is a left side elevational view of a portable cafeteria counter unit illustrated in Figure 1;

Figure 4 is a rear elevational view of the portable cafeteria counter unit illustrated in Figure 1;

Figure 5 is a right side elevational view of the portable cafeteria counter unit illustrated in Figure 1.

Figure 6 is a front elevational view thereof.

I claim:

The ornamental design for a portable cafeteria counter unit, substantially as shown.
